US0D1106770S

(12) **United States Design Patent** (10) **Patent No.:** **US D1,106,770 S**
(45) **Date of Patent:** **** Dec. 23, 2025**

(54) **COOLER**

(71) Applicant: **PepsiCo, Inc.**, Purchase, NY (US)

(72) Inventors: **Michel Alvarez**, Miami, FL (US); **Xavier Cortadellas**, Hallandale Beach, FL (US); **Sean Joseph Huls**, Chicago, IL (US); **William Owen Stock**, Chicago, IL (US); **Matthew K. Lider**, North Bend, WA (US); **Yang Ouyang**, Sammamish, WA (US); **David Robert Schlesinger**, Seattle, WA (US); **Joshua Stough**, Kirkland, WA (US); **Sarah White**, Redmond, WA (US)

(73) Assignee: **PepsiCo, Inc.**, Purchase, NY (US)

(**) Term: **15 Years**

(21) Appl. No.: **29/982,028**

(22) Filed: **Jan. 3, 2025**

Related U.S. Application Data

(63) Continuation of application No. 29/937,129, filed on Apr. 12, 2024, now Pat. No. Des. 1,059,113, which is a continuation of application No. 29/855,301, filed on Sep. 30, 2022, now Pat. No. Des. 1,022,568.

CLAIM

The ornamental design for a cooler as shown and described.

DESCRIPTION

FIG. 1 is a top front isometric view of a cooler showing the claimed design;

FIG. 2 is a bottom rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures show portions of the cooler that form no part of the claimed design.

1 Claim, 8 Drawing Sheets
